FOREIGN PATENT DOCUMENTS

CN 304572483 * 4/2018

Primary Examiner — T Chase Nelson*Assistant Examiner* — Mary Claire Ramirez(74) *Attorney, Agent, or Firm* — WPAT, PC(57) **CLAIM**

The ornamental design for a camera, as shown and described.

DESCRIPTION

FIG. 1 is a bottom perspective view of a camera showing the new design in a first embodiment;

FIG. 2 is a front view thereof;

FIG. 3 is a rear view thereof;

FIG. 4 is a left view thereof;

FIG. 5 is a right side view thereof;

FIG. 6 is a top side view thereof;

FIG. 7 is a bottom view thereof;

FIG. 8 is bottom perspective view of a second embodiment of the camera showing the new design;

FIG. 9 is a front view thereof;

FIG. 10 is a rear view thereof;

FIG. 11 is a left view thereof;

FIG. 12 is a right side view thereof;

FIG. 13 is a top side view thereof; and,

FIG. 14 is a bottom view thereof.

The broken lines in the drawings depict portions of the camera that form no part of the claimed design.

1 Claim, 14 Drawing Sheets---
